UNITED STATES PATENT OFFICE.

CHARLES FERO, SR., OF BAY CITY, MICHIGAN, ASSIGNOR OF ONE-HALF
TO JACOB P. BENDER, OF WEST BAY CITY, MICHIGAN.

ENGINE.

No. 802,384.

Specification of Letters Patent.

Patented Oct. 24, 1905.

Application filed September 12, 1904. Serial No. 224,197.

To all whom it may concern:

Be it known that I, CHARLES FERO, Sr., a citizen of the United States, residing at Bay City, in the county of Bay and State of Michigan, have invented certain new and useful Improvements in Engines; and I do declare the following to be a full, clear, and exact description of the invention, such as will enable others skilled in the art to which it appertains to make and use the same.

This invention relates to improvements in engines, and particularly to marine engines.

The object of the invention is to provide an engine of this character by which the entire expansive power of the steam is utilized.

A further object is to provide an engine of this character which may be stopped, started, or reversed from either side.

Another object is to provide means whereby the pressure of steam which is ordinarily exerted upon the cylinder-heads is utilized to aid in turning the crank-shaft.

Still another object is to provide an antifrictional bearing between the connecting-rods and the cranks on the drive-shaft.

With these and other objects in view the invention consists of certain novel features of construction, combination, and arrangement of parts, as will be more fully described, and particularly pointed out in the appended claims.

In the accompanying drawings, Figure 1 is a vertical longitudinal sectional view of a marine engine constructed in accordance with the invention. Fig. 2 is a side elevation of the engine. Fig. 3 is a detail vertical transverse sectional view through one of the slide-valves. Fig. 4 is a detail sectional view through the end of one of the connecting-rods, showing the manner of connecting said rods with the cranks of the drive-shaft.

In the embodiment of the invention I provide an upright engine consisting of a supporting-frame 1, in the lower end of which is journaled a drive-shaft 2. In the upper end of the frame is arranged a centrally-disposed main cylinder 3, and on each side of the same are arranged auxiliary cylinders 4, which are of considerably less diameter than the main cylinder 3. On the outer side of the cylinders 4 are arranged cylindrical valve-chambers 5.

In the main cylinder 3 are adapted to work three pistons 6, 7, and 8, the pistons 6 and 8 of

which are spaced apart and connected to a centrally-disposed piston-rod 9, which is adapted to pass through a centrally-disposed packed opening in the piston 7. The piston 7 is connected to the ends of two piston-rods 10, which are arranged on each side of the rod 9 and pass through packed openings in the piston 8. In the cylinder 4 are arranged combined pistons and valves 12, which are connected to piston-rods 13. In the valve-chambers 5 are arranged hollow reciprocating valves 14, to which are connected downwardly-projecting valve-stems 15.

The piston-rod 9 projects through a stuffing-box 16 in the lower end of the cylinder 3 and is connected at its lower end to a cross-head 17, which is slidably mounted in a guideway 18, arranged in the frame 1 below the cylinders, and to said cross-head is pivotally connected the upper end of a connecting-rod 19. The piston-rods 10 project through stuffing-boxes 20, also formed in the lower end of the cylinder 3, and are connected to cross-heads 21, which are slidably mounted in guideways 22, arranged in the frame 1 adjacent to the guideway 18, and to said cross-heads 21 are pivotally connected the upper ends of connecting-rods 21'. The piston-rods 13 pass through stuffing-boxes 23 in the lower ends of the cylinders 4 and are connected to cross-heads 24, which are slidably mounted in guideways 25, which are arranged in the frame 1, and to said cross-heads are pivotally connected the upper ends of connecting-rods 28.

The valve-stems 15 project downwardly through guide-passages in the frame 1 and have formed on their lower ends laterally-projecting headed pins or bolts 29, with which are adapted to be removably connected eccentric-rods 30, the opposite ends of which are connected to the straps of eccentrics 31, which are mounted on the drive-shaft 2.

On the lower end of the connecting-rod 19 is formed an antifrictional bearing 32, by which said rod is connected to a centrally-disposed crank 33, formed on the drive-shaft 2. On the lower ends of the connecting-rods 21' are formed similar bearings 32, by which said rods are connected with cranks 34, formed on the drive-shaft 2, the cranks 33 and 34 being disposed diametrically opposite each other. The connecting-rods 28 of the valve-pistons 12 are also provided at their lower ends with

antifrictional bearings 32, by which the same are connected to cranks 35 on the drive-shaft. The upper ends of the connecting-rods 30, which are engaged with the pins or bolts 29, have formed therein notches or recesses 36, by which the rods 30 may be connected to said pins or bolts 29.

In the side walls of the main cylinder and communicating between the same and the auxiliary cylinders 3 are formed pairs of ports 38 and 39, said pairs of ports serving alternately as inlet and exhaust ports, the ports 38 admitting and discharging steam to and from the space between the pistons 7 and 8, while the ports 39 admit and discharge steam to and from the space between the pistons 6 and 7.

In the wall of the cylinders 4 opposite to the ports 38 and 39 are formed ports 40 and 41, which are arranged near the ends of said cylinder and also serve to alternately admit and discharge steam to and from the cylinders 4. In the cylinders 4 are also formed main-cylinder exhaust-ports 42, through which the exhausted steam from the main cylinder is discharged, the pistons 12 being provided with an annular depression or recess between the ends or heads of the same, thereby forming with the walls of the cylinder an annular space 43, which, as the pistons 12 are reciprocated in the cylinders 4, will alternately communicate with the ports 38 and 39, and when in communication with the same will receive the exhausted steam from between the pistons of the main cylinders and permit it to discharge through the discharge-ports 42. The hollow cylindrical sliding valves 14 in the cylinders 5 are adapted to alternately cover and uncover the ports 40 and 41, thereby controlling the admission and discharge of steam to the cylinder 4.

In each of the valve-cylinders 5 is formed a main steam-inlet passage 44 and a discharge-passage 45, through which exhaust-steam from each end of the cylinder 4 is adapted to pass.

Assuming the engine to be in the position shown in Fig. 1, wherein the pistons 7 and 8 are at their nearest approach and forming between themselves a narrow steam-space with which the ports 38 communicate, said ports are at this time inlet-ports. Steam is supposed to be entering the valve-chambers 5 on each side of the engine through the main inlet-ports 44 at one end of the chambers and from thence passes through the hollow valves 14 to the opposite end of the chambers, the valves 14 being at this time in position to close the ports 41 and open the ports 40, through which latter ports the steam now passes into the cylinders 4, the pistons 12 in said cylinders 4 being in position to open the ports 38, thereby permitting the steam to pass from the cylinders 4 into cylinder 3 between the pistons 7 and 8, where it expands against said pistons, forcing

the piston 7 upwardly toward the piston 6 and the piston 8 downwardly toward the lower end of the cylinder. The pistons 8 and 6 being fixed on the same piston-rod will of course move together. Thus when the piston 8 is moved downwardly the piston 6 will also move downwardly or toward the piston 7, said pistons 6 and 7 approaching each other until they are nearly engaged, as shown in dotted lines in Fig. 1, thereby forming a contracted space opposite to and with which the ports 39 will communicate. When the pistons 12 are in position to permit the steam in the cylinders 4 to pass out of the ports 38 and into the space between the pistons 7 and 8, the ports 39 will be uncovered by the pistons 12, so as to connect the space in the cylinder 3 between the pistons 6 and 7 with the space 43 between the ends of the pistons 12, thereby permitting the steam from the space between the pistons 6 and 7 to exhaust into the space 43 as said pistons come together. This exhausted steam after passing into the space 43 is discharged through the discharge-ports 42. When the pistons 8, 7, and 6 in the main cylinders have been moved by the steam to the dotted-line positions, as just described, the eccentric disks 31 on the drive-shaft will have shifted the valves 14 through the connecting-rods 30 to cover the inlet-valve 40, so that live steam cannot pass through the same, this port being now in communication with an exhaust-steam space 46, formed around the valves 14, similar to the exhaust-steam spaces formed around the valves 12 and with which spaces 46 are connected with the discharge-ports 45. When the valves 14 have been thus shifted to cover the ports 40, the ports 41 at the opposite ends of the same will be uncovered, thereby permitting the live steam which enters at this end of the valve-chambers through the main supply-ports 44 to pass directly into this end of the cylinders 4. The pistons 12 in said cylinders having by this time been shifted to uncover the ports 39, the live steam will enter the cylinder 3 through these ports and will pass between the cylinders 6 and 7, which have been brought together opposite said ports, as previously described, and will expand, thereby forcing the same apart and back to their former position, wherein the first-described movements will be repeated, thus driving the engine. As the pistons 12 move downwardly to uncover the ports 39 the ports 38 will be thereby covered and connected with the steam-exhaust spaces around the pistons 12, whereby the exhausted steam from between the pistons 7 and 8 in the main cylinder is permitted to exhaust through the discharge-ports 42, this movement of the pistons 12 alternately transforming the ports 38 and 39 from inlet to exhaust ports, while the shifting of the valves 14 alternately transform the ports 40 and 41 into inlet and exhaust ports to admit and discharge steam.

from the opposite ends of the cylinders 4, as hereinbefore described.

Pivotedly mounted in the upper end of the frame 1 are hand-levers 50, the inner ends of which are pivotally connected with the stems 15 of the valves 14, whereby said valves may be manually operated to start, stop, or reverse the movement of the engine. When the valves 14 are thus manually operated by the levers 50 at either side of the engine, the eccentric-rod 30 should be disconnected or unhooked from the pin or bolt 29 on the stem of the valves operated thereby until after the engine has been started or reversed, when said eccentric-rod will again be connected with the valve-stem, so that the movement of the valve will be continued by the eccentrics on the drive-shaft.

Pivotedly connected to the piston-rods 13 of the piston-valves 12 are connecting-bars 51, which are adapted to be swung into and out of engagement with flanged collars 52, secured to the valve-stems 15, whereby said piston-rods and valve-stems may be connected together to cause the slide-valves 14 and pistons 12 to move in unison. During the normal operation of the engine the arms 51 are disconnected from the valve-stems 15, and the latter are connected to the eccentric 30. The throw of the eccentrics 31, which normally operate the valves 14, is considerably less than that of the cranks 35. When getting under way, it is necessary to move the valves 14 to the maximum extent. Hence under these conditions they are connected to the valves 12 by the arms 51 and disconnected from the eccentrics 31; but when the engine is to be run under normal conditions and with the greatest possible economy the valves 14 are disconnected from the valves 12 and connected to and operated by the eccentrics 31 to cut off the valve 14 at partial stroke of the piston-valve to employ the steam expansively, as will be understood.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus described my invention, what I claim as new, and desire to secure by Letters Patent, is—

1. In an engine of the class described, the combination with a main cylinder, of auxiliary cylinders connecting with said main cylinder through inlet and exhaust ports, multiple opposing pistons arranged in said main cylinder, piston-valves arranged in said auxiliary cylinders whereby the inlet and exhaust of steam to and from said main cylinder is controlled,

piston-rods connected to the pistons in said main and auxiliary cylinders, a drive-shaft, cranks formed on said drive-shaft, connecting-rods connecting said cranks with the piston-rods of pistons, and valves operated by said drive-shaft to control the inlet and exhaust of steam to said auxiliary cylinders, substantially as described. 70

2. In an engine of the class described, the combination with a main cylinder, of auxiliary cylinders connecting with said main cylinder through inlet and exhaust ports, multiple opposing pistons arranged in said main cylinder, piston-valves arranged in said auxiliary cylinders whereby the inlet and exhaust of steam to and from said main cylinder is controlled, piston-rods connected to the pistons in said main and auxiliary cylinders, a drive-shaft, cranks formed on said drive-shaft, connecting-rods connecting said cranks with the piston-rods of pistons, valve-cylinders connected with said auxiliary cylinders, through inlet and exhaust ports formed therein, said cylinders having also formed therein steam supply and discharge ports, hollow reciprocating valves arranged in said cylinders, means whereby said valves may be connected with and operated by said drive-shaft, substantially as described. 85

3. In an engine of the class described, the combination with a main cylinder, of auxiliary cylinders connecting with said main cylinder through inlet and exhaust ports, multiple opposing pistons arranged in said main cylinder, piston-valves arranged in said auxiliary cylinders whereby the inlet and exhaust of steam to and from said main cylinder is controlled, piston-rods connected to the pistons in said main and auxiliary cylinders, a drive-shaft, cranks formed on said drive-shaft, connecting-rods connecting said cranks with the piston-rods of pistons, valve-cylinders connected with said auxiliary cylinders through inlet and exhaust ports formed therein, said cylinders having also formed therein steam supply and discharge ports hollow, reciprocating valves arranged in said cylinders, stems secured to said valves, eccentrics mounted on said drive-shaft, eccentric-rods connected to said eccentrics, and means whereby the said rods may be detachably connected to the stems of said valves, substantially as described. 100

4. In an engine of the class described, the combination with a main cylinder, of auxiliary cylinders connecting with said main cylinder through inlet and exhaust ports, multiple, opposing pistons arranged in said main cylinder, piston-valves arranged in said auxiliary cylinders whereby the inlet and exhaust of steam to and from said main cylinder is controlled, piston-rods connected to the pistons in said main and auxiliary cylinders, a drive-shaft, cranks formed on said drive-shaft, connecting-rods connecting said cranks with the piston-rods of the pistons, and valve-cylinders connected with said auxiliary cylinders through 130

inlet and exhaust ports formed therein, said cylinders having also formed therein steam supply and discharge ports hollow, reciprocating valves arranged in said cylinders, stems 5 secured to said valves, eccentrics mounted on said drive-shaft, eccentric-rods connected to said eccentrics, said eccentric-rods being provided with notches whereby the same are detachably connected with the stems of said 10 valves and means whereby said valves may be manually operated to start, stop and reverse the engine, substantially as described.

5. In an engine of the class described, the combination with a main cylinder, of auxiliary 15 cylinders connecting with said main cylinder through inlet and exhaust ports, multiple opposing pistons arranged in said main cylinder, piston-valves arranged in said auxiliary cylinders whereby the inlet and exhaust of steam 20 to and from said main cylinder is controlled, piston-rods connected to the pistons in said main and auxiliary cylinders, a drive-shaft, cranks formed on said drive-shaft, connecting-rods connecting said cranks with the piston- 25 rods of pistons, valve-cylinders connected with said auxiliary cylinders through inlet and exhaust ports formed therein, said cylinders having also formed therein steam supply and discharge ports hollow, reciprocating 30 valves arranged in said cylinders, stems secured to said valves, eccentrics mounted on said drive-shaft eccentric-rods connected to said eccentrics, said eccentric-rods being provided with notches, whereby the same are de-

tachably connected with the valve-stems of 35 said valves, pivotally-mounted hand-levers connected to said valve-stems whereby said valves may be manually operated to start, stop and reverse the engine and means whereby 40 by said valve-stems and auxiliary piston-rods may be detachably connected together to cause said valves and pistons to move in unison, substantially as described.

6. In an engine of the class described, the combination with a main cylinder, of auxiliary 45 cylinders connecting with said main cylinder through inlet and exhaust ports, multiple opposing pistons arranged in said main cylinder, piston-valves arranged in said auxiliary cylinders whereby the inlet and exhaust of steam 50 to and from said main cylinder is controlled, piston-rods connected to the pistons in said main and auxiliary cylinders, a drive-shaft, cranks formed on said drive-shaft, connecting-rods connecting said cranks with the piston- 55 rods of pistons, antifrictional bearings formed in the connections between said connecting-rods and cranks, and valves operated by said drive-shaft to control the inlet and exhaust of steam to said auxiliary cylinders, substantially 60 as described.

In testimony whereof I have hereunto set my hand in presence of two subscribing witnesses.
